UNITED STATES PATENT OFFICE.

MILLER BRONSTHER, OF BROOKLYN, NEW YORK, ASSIGNOR TO THE ANCHOR MFG. CO., OF NEW YORK, N. Y., A COPARTNERSHIP CONSISTING OF HENRY BRONSTHER AND MILLER BRONSTHER.

DESIGN FOR A COVERED DISH.

Application filed November 30, 1927. Serial No. 24,340. Term of patent 7 years.

To all whom it may concern:

Be it known that I, MILLER BRONSTHER, a citizen of the United States, residing in the borough of Brooklyn, county of Kings, city and State of New York, have invented a new, original, and ornamental Design for a Covered Dish, of which the following is a specification, reference being had to the accompanying drawing, forming part thereof.

cle showing my new design; Figure 2 is a plan view of the dish portion; Figure 3 is a side elevation of the dish portion; Figure 4 is a plan view of the cover portion; and Figure 5 is a side elevation of the cover portion.

I claim:

The ornamental design for a covered dish as shown.
